UNITED STATES PATENT OFFICE,

CHENEY KILBURN, OF PHILADELPHIA, PENNSYLVANIA.

BED-BOTTOM.

SPECIFICATION forming part of Letters Patent No. 339,789, dated April 13, 1886.

Application filed June 4, 1884. Serial No. 133,822. (No model.)

To all whom it may concern:

Be it known that I, CHENEY KILBURN, a citizen of the United States, residing at Philadelphia, in the county of Philadelphia and 5 State of Pennsylvania, have invented certain new and useful Improvements in Bed-Bottoms, of which the following is a specification, reference being had therein to the accompanying drawings.

10 Figure 1 is a top or plan view. Fig. 2 is an edge view of one of the sides. Fig. 3 is an edge view of one of the ends. Fig. 4 is a partial section on line $x x$, Fig. 1. Fig. 5 is a detached view of one of the socket-pieces. 15 Fig. 6 is a detached view of one of the supporting-legs.

My invention relates to that class of beds in which the mattress rests upon a series of thin flat elastic steel strips or ribbons; and 20 it consists in certain details of construction, as will be hereinafter fully explained.

The frame consists of end bars, side bars, and connecting socket-pieces, which are constructed substantially as follows:

25 A A are the end rails, each made by preference of wood, and provided at each end with a horizontal transverse opening or seat, a . I prefer to make these end bars of wood, but do not wish to be limited to the use of any 30 particular material.

B B' are the side rails, each having right and left hand threads $b b$ at its ends. By preference I make these rails of gas-pipe, and combine therewith a wooden core, B', which 35 strengthens them materially against sidewise deflection, it being well understood that no serious deflection can occur so long as the tube is prevented from collapsing, and this liability I obviate by means of the cores B', which 40 are made of such size as to fit tightly within the tubing or gas-pipe.

The end rails and side rails are connected together by corner-pieces, preferably of metal, and consisting of the open forked part C C 45 and inwardly-projecting shank or neck C', which by preference is round in cross-section. Each corner-piece has a threaded socket, c, adapted to receive one of the threaded ends b of a side rail. The space between the forked 50 ends is of such width as to receive one end of the end rail, A, and is in the same horizontal plane as the shank portion which receives the

side rails, the hole a of the end rail being in such position as to register with the screw-threaded socket c . By preference these holes a are of such size as to fit closely the threaded ends of the side rails, so that when the parts are joined together, as in the drawings, the ends of the side rails not only prevent the corner-pieces and side rails from 60 sliding longitudinally on the end rails, but also prevent the end rails from being moved out of the forked ends of the corner-pieces and off from the ends of the side rails.

The fabric upon which the mattress rests is 65 composed of thin longitudinal strips or ribbons D D, of steel, transverse thin strips or ribbons E E, also preferably made of steel, and the spiral springs d d, which are interposed between and connect the strips D E with 70 the end rails at, preferably, both ends of the bed. The strips or ribbons D E are riveted at their intersections, and may be interlaced, or all of the strips D may be upon either the upper or the lower sides of the strips E, or part 75 of the transverse strips may be upon one side of the longitudinal strips and a part upon the other side, as shall be found desirable.

It is evident that the jaws or forks of the corner-pieces may be strengthened to any desired extent by increasing the height or breadth of the re-enforcing ribs c'.

By leaving the outer ends of the fork open, instead of uniting them by a web or tie, I am enabled to screw the side rails into the corner-pieces such distance that the ends of the side rails will project beyond the outer edges of the end rails, thus enabling me to hook or otherwise connect the ends of the spiral springs d with the ribbons or strips D D and the end rails, A, after which proper tension upon the springs may be produced by turning the side rails in the reverse direction, but without withdrawing the ends of the side rails from the holes a , and, when preferred, the length 85 of the neck or shank C' beyond the threaded seat c may be such that the end rails may be spread apart sufficiently without exposing to view the screw-threads on the side rails, as indicated in dotted lines, Fig. 1, this result being attained with but little increase in weight 90 of the corner-pieces. Another advantage which is gained by such increased length of the neck C' is the support which is thus af- 100

forded to the frame against twisting or swinging out of shape.

In Figs. 3 and 5 I have shown a modification of the devices which I propose to employ for preventing the side rails from moving toward or from the ends of the end rails. At the left-hand end of Fig. 3, in which the parts are partially broken away, the end rail has upon its upper surface transverse grooves, notches, or recesses $a' a'$, and the upper arm or jaw of the forked end C' of the corner-piece is provided upon its under surface with pins, spurs, or webs $c' c'$, which fit into the recesses or grooves a' . By an examination of the drawings it will be seen that by reason of the engagement of these projections c' with the walls of the transverse seats a' the side rails are locked to each other in such manner as to prevent the side rails from moving or sliding toward or from the ends of the end rails, even though the threaded ends of the side rails did not project through the socket portions C of the corner-pieces and into the circular seats or holes a of the end rails. Therefore I do not wish to be limited to the use of both of these sets of projections and transverse seats, because when those marked $c a$ are employed, those which are marked $a' c'$ may be omitted, and vice versa.

30 The size of the frame-work should be such as to fit within the end and side rails of a bedstead of ordinary construction, and may be made of various sizes, as is customary in the manufacture of woven-wire and other similar spring-beds.

The supporting-legs each consist of the vertical part F , the upper horizontal arm, f , and the foot f' , which latter is adapted to rest upon the rib f^2 , which is attached to the inner face of the side rail of a bedstead of the ordinary construction. The upper arm, f , is seated in a recess, c^2 , which is formed in the lower leg or arm of the fork, and between that leg and the end rail, A , one at each corner of the bed. These legs may be adjusted by sliding them out or into the recesses so far as to fit the bedsteads of different widths.

The part F may be made of different lengths, in order to raise the frames to different heights 50 from the rib f^2 , as may be required, it being possible by means of supporting-legs of this construction to mount the bed-bottom very low in the bedstead, even though the latter be considerably wider than the former, by making the part F shorter than shown in the drawings, this being secured without in any manner weakening the legs.

It will be seen that the side rails and the corner pieces together form an extensible side 60 bar or rail, which is adapted to interlock with and hold the end rails against both longitudinal and endwise movement, and that this locking together or uniting of the rails or bars which form the frame of the bed-bottom is accomplished without the use of any removable or supplemental parts—such as screws, dowel-pins, nails, &c.—as have heretofore been em-

ployed. This side rail is provided at its ends with seats for the reception of the end bars, which seats are in the outer parts of the side 70 rails, and are so situated relatively to the movable parts of the rail that after the end bar has been placed in the seat the part of the extensible rail which projects into the transverse seat interlocks with the end bar, and thus holds 75 the two rails together. The seat in the side rail prevents movements of the end rail in certain directions, (vertical in the form shown,) while the interlocking part of the side rail prevents movements in other directions. However, 80 should this seat open outwardly, as shown, and the part B of the side rail be not screw-threaded but held by a set-screw or otherwise, in such event the tension of the longitudinally-elastic fabric upon which the mattress is supported would hold the end rails 85 in their seats against longitudinal movement.

The best method of which I am aware for uniting the parts of the extensible side bar is by means of a screw-connection such as shown, 90 which gives the necessary extensibility, and enables me to use a gas-pipe or other plain body for the side rail, and a perfectly plain end rail, say rectangular in cross-section.

I am aware that an extensible end rail for 95 bed-bottoms consisting of a cylindrical rail and a nut seated in a socket in the wooden side bar, has been used to stretch the mattress-supporting fabric, and hence I do not claim such a device as my invention; but by the employment of the seats in the corner-pieces or outer parts of the side rail, which embrace the side bars, I entirely overcome or avoid any tendency to split or fracture the parts when the side bar B is being turned to extend the side 105 bars, and so, also, the forked corner-pieces firmly support the end bars against any tendency to splitting under strain. Again, the metallic legs F , supported in the corner-pieces, as shown, are firmly held in place by the adjacent parts, and are practically free from 110 danger of breakage or of being misplaced under the ordinary wear to which they are subjected when in use.

I am aware that it is old to form a bed-bottom 115 of side rails having screw-threaded ends, end rails, and corner-pieces connecting the side and end rails, and having screw-threaded seats or sockets for the side rails, and seats for the end rails arranged in a plane above the 120 seats for the side rails, and hence I do not claim a corner-piece of such construction as my invention.

What I claim is—

1. In a bed-bottom, the combination, with 125 the end rail provided with transverse seats, of the side rails, each having at one end a corner-piece with a seat the inner walls of which are adapted to embrace the end rail, and each also having a projection which enters the transverse seat of the end rail, substantially as set forth.

2. In a bed-bottom, the combination, with 130 the end rails provided with transverse seats,

of the extensible side rails having at their ends corner-pieces provided with seats the walls of which are adapted to embrace the side rails, and projections on the side rails which enter the transverse seats of the end rails, substantially as set forth.

5. In a bed-bottom, the combination, with the end rails provided with transverse seats, of the extensible side rails having at their ends corner-pieces provided with seats the walls of which are adapted to embrace the end rails, and projections on the side rails adapted to enter and be rotated within the transverse seats of the end rails, substantially as set forth.

10. In a bed-bottom, the combination, with the end rails provided with transverse seats, of the side rails having at their ends forked corner-pieces provided with outwardly open seats to receive the end rails, and projections adapted to enter the transverse seats of the end rails, and the elastic fabric adapted to retain the end rails in the outwardly-open seats, substantially as set forth.

15. In a bed, the combination, with the bed-bottom, of the herein-described metallic legs arranged to support the bed-bottom within a bedstead, said leg being adjustable relatively to the bed-bottom, and consisting of the vertical portions F, the upper horizontal portions, f, attached to the bed-bottom, and the feet portion f', substantially as set forth.

20. In a bed, the combination, with a bed-bottom having corner-pieces provided with the forked parts C C, between which the end rails lie, of the legs which support the bed-bottom in a bedstead seated in recesses c² formed in the parts C of the corner-pieces and adjustable in said recesses, substantially as set forth.

25. In testimony whereof I affix my signature in presence of two witnesses.
